UNITED STATES PATENT OFFICE.

L. B. FLANDERS, OF PHILADELPHIA, PENNSYLVANIA.

IMPROVEMENT IN APPARATUS FOR BORING CYLINDERS.

Specification forming part of Letters Patent No. 44,296, dated September 20, 1864.

To all whom it may concern:

Be it known that I, L. B. FLANDERS, of Philadelphia, Pennsylvania, have invented an Improved Portable Boring Apparatus; and I do hereby declare the following to be a full, clear, and exact description of the same, reference being had to the accompanying drawings, and to the letters of reference marked thereon.

My invention relates to improvements in apparatus for boring out cylinders, my said improvements, which are fully described hereinafter, being such that the apparatus can be readily adapted to the boring out of horizontal, vertical, or inclined cylinders without removing the same from their foundations or framework. The apparatus is also applicable to the boring out of other large objects—such, for instance, as the hubs of fly-wheels or the bearings of heavy shafts.

In order to enable others skilled in the art to make and use my invention, I will now proceed to describe its construction and operation.

On reference to the accompanying drawings, which form a part of this specification, Fig. 1, Drawing No. 1, is a section of my improved portable boring apparatus; Fig. 2, a plan view; Fig. 3, a sectional plan on the line 1 2, Fig. 1; Fig. 4, a plan view of part of the machine; Fig. 5, a device to be sometimes used in connection with the machine; Fig. 6, (Drawing No. 2,) a plan view of the cutting-head; Fig. 7, a vertical section of part of the cutting-head, drawn to an enlarged scale; Fig. 8, a plan view of a plate employed when the machine has to be used for boring vertical cylinders; Fig. 9, an edge view of the plate, Fig. 8; Fig. 10, a sectional view of a device to be used in boring either vertical or horizontal cylinders; and Fig. 11, a transverse section on the line 3 4, Fig. 10.

On reference to Figs. 1, 2, 3, and 4, Drawing No. 1, A represents a horizontal or inclined cylinder from which both heads have been removed, and B is the boring-bar, which has a longitudinal groove for the reception of the feeding-screw C.

To the flange a, at one end of the cylinder, is secured a cross-plate, D, by means of suitable bolts, b, in such a manner that the said

plate can be readily adjusted laterally on the flange of the cylinder. The central portion of this plate D is made in the form of a ring, (see Fig. 4,) through which pass four set-screws, c, the latter serving to confine and adjust within the ring the bearing or sleeve E, in which the boring-bar B turns, a movable collar, d, on the bar bearing against the said sleeve. A somewhat similar cross plate, D', is secured to blocks F, the latter being attached to the flange e at the opposite end of the cylinder A, and a sleeve, E', is secured to this plate, as in the former case, by set-screws, thus forming another bearing for the boring-bar B. An adjustable collar, e', surrounds the boring-bar, to which it is secured by suitable set screws, this collar being confined within the sleeve E by an annular piece, f, which fits into the sleeve, and is secured to the same by pins or keys, the collar e' thus preventing any longitudinal movement of the boring-bar.

G is the cutting-head, which fits snugly but so as to slide freely on the boring-bar, the head having in the present instance three cutters, h, as best observed on reference to Fig. 6, Drawing No. 2. The cutters h fit into and are guided by slots in the head, to which they are secured by plates i. Small studs i', screwing into the hub j of the head, and bearing against the rear of the cutters, serve to adjust the same and to maintain them at a proper distance from the center of the bar. A block, k, fits snugly in an opening in the hub j of the cutting-head, to which it is confined by set-screws or other suitable appliances, the inner face of the block having threads cut in it so as to fit those on the longitudinal screw C, of which the block thus forms the nut, so that on turning the said screw the cutting-head must traverse the boring-bar. This nut, however, serves another purpose, for besides fitting to the screw it fits snugly to the sides of the longitudinal slot which contains the screw, and thus acts as a key to prevent the boring-bar from turning independently of the cutting-head. The boring-bar passes through and turns freely in a case, H, composed of two plates secured to each other, and within this case are the three cog-wheels I, J, and K, the wheel I being so secured to the boring-bar

that the latter can slide freely through the former, but so that one cannot turn independently of the other, and this wheel I gears into the wheel J on a spindle, which turns in the case H, the latter wheel gearing into the wheel K on a spindle, L, which, in the present instance, is provided with a hand-wheel or with a driving-pulley, L', for receiving a belt from any adjacent shaft.

It should be understood that the casing H must be held stationary by any suitable attachments.

To the extreme end of the boring-bar is secured another casing, M, within which is confined the feeding-gear, the latter consisting of a cog-wheel, m, on the end of the longitudinal screw C, the said wheel gearing into a pinion, m', on a spindle which turns in the casing, the said spindle being provided with another wheel, n, gearing into a pinion, n', on a shaft, p, which turns in the cover of the casing M, and which is provided with a suitable handle, q, this shaft being exactly central with the boring-bar.

The several parts having been thus arranged, the cutting head having, by turning the screw C, been moved to that end of the cylinder from which the boring has to be commenced, and the cutters having been properly adjusted, motion is communicated to the shaft L and through the train of wheels K, J, and I to the boring-bar B. As the latter revolves, a rotary motion will necessarily be communicated from the cog-wheel m, and through the wheels m', n, and n' to the shaft p, and the cutting-head will continue to revolve without traversing the boring-bar; but if the shaft p be held stationary by means of the handle q, the longitudinal screw-shaft C must necessarily turn on its own axis and impart a movement to the cutting-head along the boring-bar, and this movement can be regulated at pleasure by the proper manipulation of the handle q.

It will be seen that the above described mechanism can be readily applied to any horizontal or inclined steam-cylinder without removing the same from the base-plate or framework of the engine, and that the apparatus can also be used for boring a variety of objects, as well as steam-cylinders.

When the boring-bar has to be adapted to vertical cylinders so situated that the use of the cross plate D at that end of the cylinder which has the stuffing-box cover is impracticable, I use the device shown in Figs. 10 and 11, Drawing No. 2, for the purpose of affording a bearing for one end of the boring-bar.

In Fig. 10 part of the cylinder-head is shown by red lines N, the follower with the packing, which together form the stuffing-box, having been removed to make way for a circular block, P, of metal, part of which is of the tapering form represented in the drawings. In this block are cut four or any other suitable number of grooves for the admission

of the keys 2, one key being so dovetailed into each groove that while all the keys can be simultaneously moved outward laterally they cannot be withdrawn from the said grooves. At the upper end of the block P is a screwed stem, u, to which is adapted a nut, u', and between the latter and the upper ends of the keys intervenes a washer, r.

The above-described device is placed in that portion of the cylinder-head previously occupied by the packing and follower, after which the nut u' is so turned as to depress the keys and cause them to bind against the interior of the packing-chamber. A projection, w, at the lower end of the block P fits into a recess in the boring-bar, which is thus supported at one end.

It will be evident that the above device is self-adjusting to the center of the cylinder, and that when the boring-bar is once fitted to the projection w its proper position is determined.

In some instances steam-cylinders are closed at one end and where there is no detachable cover. In such cases I adopt the devices illustrated in Figs. 8 and 9 for forming a bearing for one end of the boring-bar.

Q is a plate, having four recesses, in each of which a bar, R, is arranged to fit snugly but slide freely, bolts s being used for confining these bars to the plate. From the center of the plate projects a pin, x, on which turns a block, T, and on the lower edge of the latter are formed four cam-shaped projections, y, each of which bears against the inner end of one of the sliding bars R. The plate, with these appliances, is deposited in the cylinder, and rests on the closed end of the same, as seen in Fig. 9. A suitable instrument is then inserted into the square portion of the opening in the block T, and the latter is so turned that its cam-like projections y shall move out the sliding pieces R simultaneously and cause them to bear tight against the interior of the cylinder, after which the bars R are secured by the bolts s, the block T is withdrawn from the pin x, and one end of the boring-bar placed over the said pin x. It will be readily seen that this device, like that above described, is self-adjusting to a central position within the cylinder.

When my boring-machine is applied to vertical cylinders, I remove the hand-wheel or pulley L', Drawing No. 1, from the shaft L, and place on the same a bevel-wheel, t, and secure to the casing H a bracket, U, carrying a spindle on which is a bevel-wheel, t', gearing into the similar wheel t, a driving-pulley, 3, being secured to the same spindle. By this arrangement the driving-pulley is presented in the proper position for receiving a belt.

I claim as my invention and desire to secure by Letters Patent—

1. The combination of the boring-bar B, its sleeves or bearings E and E', and the cross-

plates D and D', with their set-screws e, the whole being constructed and arranged for application to and for the adjustment of the boring-bar central with a cylinder, substantially as set forth.

2. The combination of the boring-bar B, the casing H, and the train of wheels I, J, and K, or their equivalents, the whole being arranged and operating substantially as described.

3. The collar e', attached to the boring-bar and confined within the sleeve or bearing E', substantially as described.

4. The block K, adapted to the cutting-head G, to the boring-bar B, and screw C, substantially as described, so as to serve as a nut for the screw and as a key for preventing the cutting-head from turning on the bar.

5. The combination of the boring-bar B, its screw C, and casing M, or its equivalent, central shaft, p, and the train of wheels herein described, or the equivalent to the same, for the purpose specified.

6. The detachable bracket U and its spindle carrying the bevel-wheel t', in combination with the casing H, its shaft L, and bevel-wheel t.

7. The tapering block P, its inclined keys 2, screw u, and nut u', the whole being constructed for central attachment to the head of a steam-cylinder, and for forming a bearing for one end of the boring bar, substantially as set forth.

8. The plate Q, its central pin, x, radial sliding bars R, and the block T, with its cam-like projections y, the whole being arranged and operating substantially as and for the purpose specified.

In testimony whereof I have signed my name to this specification in the presence of two subscribing witnesses.

L. B. FLANDERS.
